WINDOW CLEANING DEVICE

Ande Bolles Halsey, New York, N. Y.

Application April 29, 1932. Serial No. 608,186

3 Claims. (Cl. 15—232)

This invention relates to improvements in window cleaning devices.

One of the objects of the invention resides in a window cleaning device by which the outside 5 of the glass panes of the upper and lower sliding sashes of a window may be cleaned without requiring a person sitting or standing upon the outside of the window sill, which relieves the person of the danger of falling during a window 10 cleaning operation.

Another feature of the invention is to provide a window cleaning implement embodying a flexible handle provided with a head on one end thereof, and means for quickly interchanging wet and 15 dry cleaning cloths therewith.

A further object is the provision of a window cleaning implement which may be captively connected to the arm of the user to prevent the accidental dropping of the implement when in use 20 should the user loose his or her grip thereon.

A still further feature is to provide a window cleaning device which is simple of construction, inexpensive of manufacture, and easy to use.

With these and other objects in view, the invention resides in the certain novel construction, 25 combination and arrangement of parts, the essential features of which are hereinafter fully described, are particularly pointed out in the appended claims, and are illustrated in the accompanying drawing, in which:

Figure 1 is a vertical sectional view through a window showing my invention in use.

Figure 2 is a perspective view of the window cleaning device per se with the cleaning cloth 30 removed.

Figure 3 is an enlarged detail side elevational view of the head with parts broken away, and shown in section.

Figure 4 is a detail perspective view of the 40 head end of the implement with the frame and clamping element separated.

Referring to the drawing by reference characters, the numeral 10 designates my improved window cleaning implement in its entirety which 45 includes broadly a handle 11 which carries an enlarged head 12 on one end thereof.

The handle 11 is constructed of stiff resilient wire, and is formed of a single piece of material 50 looped midway between its ends to provide a pair of spaced parallel arms 13—13, which arms are joined by cross pieces 14 which bridge the space between the arms for the purpose of preventing the arms from spreading and to provide grip portions for the hand of the user. The cross pieces

14 are arranged in spaced relation along the length of the arms 13.

The free ends of the arms 13 are fixedly connected to a wire frame 15 which is rectangular in configuration and constructed of wire. The frame 60 15 constitutes part of the head 12 and associated therewith is a smaller frame 16 of a corresponding shape as the frame 15 and is connected to the frame 15 at the corners by angular connecting members 17, the angles of which extend inward. 65 Covering the frame 16 and fitting against the connecting members 17 is a wire mesh screen 18, the free edges of which are bent inwardly around the frame 15 as best seen in Figure 3 of the drawing. The wire screen 18 by following the shape of the 70 connecting members 17 provides a channel or groove 19 around the head 12 for a purpose to be presently explained.

Associated with the head 12 is a clamping member 20 which is constructed of a single length of 75 resilient wire bent into rectangular configuration to conform to the general shape of the head 12. The clamping member 20 is normally of a size less than the size of the smaller frame 16 of the head to require the spreading of the clamping 80 member in order to pass the same over the head 12 when it is desired to clamp a cleaning cloth upon the said head. The clamping member 20 as before stated is formed from a single length of wire bent midway between its ends and which is 85 formed with an eye 21 to which one end of a flexible chain 22 connects, the opposite end of the said chain being fixedly connected to one of the cross pieces 14 of the handle 11.

Tied to one of the cross pieces 14 is one end of 90 a flexible cord 23, the opposite end being looped and tied to provide a sliding notch 24 which provides an adjustable wrist or arm loop 25.

In practice, either a wet or dry cloth such as shown in Figure 3 by the numeral 26 is placed 95 over the screen of the head 12 so that the edges of the cloth embrace the sides of the head and are received in the channel or groove 19 extending therearound. After the cloth has thus been positioned, the clamping member 20 is expanded 100 over the head and when released, is seated within the channel 19 to securely grip or clamp the cloth 26 in position which stretches the cloth 26 taut across the outer flat face of the head 12.

In Figure 1 of the drawing I have illustrated 105 my invention in use wherein A designates the upper sash of a window, and B the inner sash, which are slidably mounted in the usual window frame C. The operator by standing upon a chair or like platform may reach out over the top of the 110

upper sash when the same has been lowered so that the wiping head of the implement may be moved over the outer surface of the glass pane. Before grasping the handle 11, the operator first 5 passes his or her wrist through the loop 25 in order to captively connect the implement to the arm of the user to avoid accidental dropping of the implement in the event that the handle should be accidentally released.

10 After the outer surface of the glass of the upper sash has been cleaned, the same may be raised to its closed position and the lower sash moved upwardly and as shown in Figure 1. The operator may insert the implement between the 15 space provided between the glass panes of the upper and lower sashes in order that the cleaning head may be brought into wiping contact with the outer surface of the glass pane of the lower sash. It will of course be understood that 20 a wet cloth 26 is first associated with the head of the implement to loosen the dirt upon the glass pane, after which the moist cloth may be removed and a dry one substituted therefor which allows the drying of the glass panes. Thus it 25 will be seen that the wet and dry cloths are interchangeable with respect to the head of the implement during the cleaning of the panes. In order to remove a cloth, it is only necessary to spread the legs of the split clamping member 21 30 and pull the same outwardly from the head 12. The clamping member 20 being captively connected to the handle 11 cannot be misplaced as the same is always in position for securing the cloth in position upon the head.

35 Although I have described the implement for use particularly in the cleaning of the outer surface of the upper and lower sash panes, it will be understood that the same may be used for cleaning the inner surface of the same, if desired.

40 Furthermore, by providing a flexible handle, it is possible to flex the same in order to impart a pressure to the head when engaged with the surface to be cleaned.

75

While I have shown and described what I deem to be the most desirable embodiment of my invention, I wish it to be understood that such changes as come within the scope of the appended claims may be resorted to if desired.

Having thus described the invention, what I claim as new and desire to secure by Letters Patent is:—

1. A window cleaning device comprising a resilient handle, a head carried by said handle, said head including a pair of wire frames of different sizes but like shape joined by inwardly extending angularly bent connecting portions and disposed in substantial parallel relation over which a wiping cloth is adapted to be arranged, and a split resilient clamping member for coaction with said angular connecting portions for securing a wiping cloth in clamped position upon said head.

2. A window cleaning device comprising a flexible handle, an enlarged head carried by said handle, said head including a pair of wire frames of different sizes but like shape joined by inwardly extending angularly bent connecting portions and disposed in substantial parallel relation over which a wiping cloth is adapted to be arranged, wire screening covering said head, and a split resilient clamping member for coaction with said angular connecting portions for securing a wiping cloth in clamped position upon said head.

3. A window cleaning device comprising an elongated resilient handle, a head carried by one end of said handle having a channel extending around the side thereof, a split resilient wire clamping member for clamping engagement with the channel in said head, an eye formed in said wire clamping member, and a chain having one end fixedly connected to said eye and its other end fixedly connected to said handle for captively connecting said clamping member to said handle.

ANDE BOLLES HALSEY.
